HAIR DRYER

Fredrick Glaser, 1000 Lake Shore Plaza,
Chicago, Ill. 60611

Filed June 15, 1970, Ser. No. 23,481

Term of patent 14 years

Int. Cl. D28—03

U.S. Cl. D86—10

FIG. 1 is a front view of a hair dryer showing my new design;

FIG. 2 is a side view of the hair dryer of FIG. 1;

FIG. 3 is a rear view of the hair dryer of FIG. 1; and

FIG. 4 is a top view of the hair dryer of FIG. 1.

The drawing has been shaded for transparency.

I claim:

The ornamental design for a hair dryer, substantially as shown and described.
